CLAIM

The ornamental design for a chest device, as shown and described.

DESCRIPTION

FIG. 1 is a side perspective view of the chest device, with the shoulder pad in an upright position;

FIG. 2 is a front view with the shoulder pad in an upright position;

FIG. 3 is a rear view with the shoulder pad in an upright position;

FIG. 4 is a right side view with the shoulder pad in an upright position;

FIG. 5 is a left side view with the shoulder pad in an upright position;

FIG. 6 is a top view with the shoulder pad in an upright position;

FIG. 7 is a bottom view with the shoulder pad in an upright position;

FIG. 8 is a side perspective view with the shoulder pad in a folded position;

FIG. 9 is a front view with the shoulder pad in a folded position;

FIG. 10 is a rear view with the shoulder pad in a folded position;

FIG. 11 is a right side view with the shoulder pad in a folded position;

FIG. 12 is a left side view with the shoulder pad in a folded position;

FIG. 13 is a top view with the shoulder pad in a folded position; and,

FIG. 14 is a bottom view with the shoulder pad in a folded position.

The broken lines in the drawings illustrate portions of the chest device and form no part of the claimed design.

1 Claim, 14 Drawing Sheets
